UNITED STATES PATENT OFFICE

2,633,327

GAS TURBINE WHEEL WITH LIQUID
COOLING MEANS

Clarence M. McDowell, Toledo, Ohio, assignor to
Packard Motor Car Company, Detroit, Mich., a
corporation of Michigan

Application March 1, 1946, Serial No. 651,208

3 Claims. (Cl. 253—39.15)

1

The invention relates generally to gas turbines and more particularly to a turbine wheel or rotor construction therefor.

The general object of the invention is to provide a novel construction for the wheel or rotor of a gas turbine, which provides for cooling the wheel so that it can safely withstand relatively high unit stresses.

Another object is to provide a novel turbine wheel construction provided with cooling means to avoid the necessity of making the wheel of highly heat-resistant material.

A further object is to provide a novel turbine wheel construction in which coolant is circulated, with the coolant making direct contact with those portions of wheel which are subject to the largest centrifugal forces.

More specifically, it is an object to provide a novel turbine wheel construction having means for circulating a coolant therein, particularly in direct contact with the portions subjected to the greatest heat, such as the blade supporting portions of the wheel proper and the supporting or retaining portions of the blades.

Still another object is to provide a novel turbine wheel construction supplied with a coolant and utilizing the rotation of the wheel to effect circulation of the coolant in contact with the portions of the wheel subjected to the greatest heat.

A still further object is to provide a novel turbine wheel construction having means for circulating coolant in contact with the peripheral portion of the wheel proper, as well as with the supporting portions of the blades, the coolant being of such character as to establish a seal in any spaces that occur between the blades and the wheel.

It is also an object to provide a novel turbine wheel construction provided with coolant circulating means utilizing the turbine fuel as the coolant and thereby eliminating the necessity of maintaining a supply of liquid other than the fuel for the operation of the turbine.

A further object is to provide a novel method of cooling a turbine wheel, utilizing the turbine fuel as the coolant and causing carbonization thereof at points where any slight leakage of coolant may occur to effect deposition of carbon to seal such points.

Still another object is to provide a novel tur-

2

bine wheel construction provided with novel coolant circulating means so constructed that it may be readily assembled in the wheel.

A still further object is to provide a novel turbine wheel construction provided with coolant circulating means adapted to supply coolant to a cavity within the wheel, the latter having a two-part construction with the two parts providing the cavity between them and permitting the assembly of the coolant circulating means as an incident to the assembly of the two parts.

Other objects and advantages will become apparent from the following description taken in connection with the accompanying drawings, in

15 which:

Figure 1 is a perspective view, on a reduced scale, of a turbine wheel embodying the features of the invention.

Fig. 2 is a fragmentary axial sectional view of 20 the turbine wheel shown in Fig. 1.

Fig. 3 is a sectional view taken on the line 3—3 of Fig. 2.

Figs. 4 and 5 are enlarged sectional views taken 25 respectively on the lines 4—4 and 5—5 of Fig. 3.

Fig. 6 is a view of a portion of the periphery of the wheel shown in the preceding figures.

Fig. 7 is a view similar to Fig. 2, but showing a modified form of construction.

The advantages of gas turbines have long been known but difficulty has been experienced in the 30 practical use thereof because of problems arising from the heat of the gas. In turbines of this type, the radially extending blades on the periphery of the wheel as well as the peripheral portion of the wheel are subjected to the high temperatures of the gas. In the early days of development of turbines of this kind, practical use of such turbines was prevented to a great extent by the lack of materials which could operate at the high temperatures resulting from the temperature of the gas and at the same time maintain sufficient strength. Highly heat-resistant materials have been developed but cost considerations have been a limiting factor in the use of such materials.

The present invention provides a construction which utilizes a cooling action on the peripheral portion of the wheel so that such portion is maintained at a lower temperature than would otherwise be the case and, therefore, permits the wheel to resist high stresses to a greater degree. In

fact, the cooling of the peripheral portion of the wheel may be sufficient to permit use of a material less resistant to heat as well as to permit a somewhat lighter construction so that the centrifugal forces involved will thereby be decreased. The cooling effect preferably not only is applied to the peripheral portion of the wheel, but also to the base or supporting portions of the blades so that such base portions will correspondingly be better able to resist the stresses to which they are subjected.

To accomplish such cooling, a turbine wheel embodying the features of the invention has a construction which provides a cavity within the wheel, circular in form and extending radially to a point adjacent the periphery of the wheel. Mounted within the cavity is a means for supplying a coolant thereto and for withdrawing the coolant therefrom after it has absorbed heat from the peripheral portion of the wheel. Preferably, the wheel is rotated relative to such means and the latter may be either held stationary or rotated at a controlled speed differing from the speed of the wheel. Said means may comprise generally a plurality of radial supply pipes within the cavity for supplying coolant in liquid form to the peripheral portion of the cavity. Such means also includes a plurality of return pipes provided with means at their outer ends, preferably in the form of scoops, for picking up the heated coolant and withdrawing it from the cavity. Thus, the rotation of the wheel is utilized to effect circulation of the fluid in the peripheral portion of the cavity and permits withdrawal of the fluid by the stationary scoops positioned in the stream of coolant tending to rotate with the wheel. The centrifugal action on the coolant also maintains the coolant in contact with the extreme peripheral portion of the wheel and thus effects a scrubbing action, resulting in a rapid transfer of heat from the metal of the wheel to the liquid coolant.

As shown in the drawings, I provide a hollow wheel body, indicated generally at 10, comprising a pair of side walls 11 and 12 spaced from each other to provide an internal circular cavity 13. The side walls 11 and 12 are integrally formed with a rim portion 14. The latter is provided with a plurality of slots 15, here shown in the shape of a T, to receive blades 16 extending radially from the wheel and of proper form to cause rotation of the wheel when gas under pressure impinges upon them in an axial direction. Each blade 16, accordingly, is provided with a T-shaped base portion 17 fitting snugly within the T-shaped slot 15. Preferably, the cavity 13 within the wheel extends radially to open into the blade slots 15 so that the cavity 13 is bounded partially by the rim portion 14 of the wheel and partially by the various base portions 17 of the blades 16.

To supply liquid coolant to the cavity 13, I provide a plurality of radially extending supply pipes 20 mounted within the cavity 13 and preferably held stationary. I also provide a plurality of return pipes 21, with the supply and return pipes mounted alternately and preferably of equal number. The return pipes 21 serve to withdraw the coolant from the cavity 13 after it has absorbed heat from the wheel. Coolant is supplied to the supply pipes 20 under pressure and as it emerges from the outer ends of the supply pipes, the rotation of the wheel tends to cause the fluid to rotate with it. Thus, the coolant will circulate in an annular path limited by the peripheral margin of the cavity.

The coolant as it rotates in an annular stream

10
5

thus may be withdrawn by projecting the return pipes 21 into such stream with an opening in the outer end of each return pipe facing in a direction opposite to the flow of coolant. Thus, I provide each of the return pipes 21 with a scoop 22 at its outer end, facing circumferentially and in a direction opposite to the flow.

In effecting a rapid transfer of heat from the wheel to the coolant, several factors enter into consideration. The coolant as it is supplied through the supply pipes 20 has a greater density than after it becomes heated from contact with the wheel. Such difference in density will tend to cause the cooler fluid to move to the extreme peripheral portion of the cavity and to force the hotter fluid toward the inner portion of the stream. Thus, with the scoops 22 located as shown in the drawings, the hotter fluid will thereby be picked up by such scoops for withdrawal from the wheel and a natural flow is thereby effected. However, the scoops 22 also have the effect of creating turbulence within the stream of coolant, which is beneficial in effecting heat transfer. The stream of coolant itself will not rotate at quite as high a speed as the wheel so that there is also a flow of coolant relative to the wheel resulting in a scrubbing action from the high centrifugal forces acting on the liquid. Such action enhances the heat transfer.

The supply pipes 20 and the return pipes 21 may be mounted within the cavity 13 in any suitable manner. In the present instance, I have shown all of such pipes threaded radially into a hub 23 centrally positioned within the cavity. The hub 23 is provided with a plurality of axially extending eccentrically positioned passages 24 communicating with the respective supply pipes 20 and opening at one side of the hub. The hub is also provided with a plurality of radially extending passages 25 connecting the return pipes 21 with a central passage 26 in the hub. To supply and withdraw fluid from the respective passages, a pair of concentric pipes 30 and 31 are threaded to the hub 23, the inner pipe 31 being of such diameter as to be located radially inside of the passages 24. Thus, coolant may be supplied to the passages 24 through the annular space between the pipes 30 and 31 while heated coolant may be withdrawn from the central passage 26 through the interior of the inner pipe 31. The pipes 30 and 31, in the present instance, extend through a central opening 32 in a hub portion of the side wall 12 of the wheel. The hub 23 is preferably journaled as at 33 on a central boss 34 provided on the inner face of the side wall 11, the boss 34, in the present instance, closing one end of the central passage 26.

With the wheel having a one-piece construction and being cast with a core to provide the coolant supply and return means and particularly for the supply and return pipes 20 and 21. The hub 23 as well as the pipes 30 and 31, of course, may be readily inserted through the opening 32 in the side wall 12. To permit insertion of the supply and return pipes, each of these is dimensioned so that it may be inserted through a blade slot 15. To facilitate handling of these pipes for such insertion, each is provided at its outer end with internal splines 35. Thus, with the splines 35, a tool having a correspondingly splined portion may be inserted into the end of the pipe and the pipe passed through the blade slot 15 and turned to thread it into the hub 23. The scoops 22 for the return pipes 21 are preferably provided

with shank portions 36 which are splined and adapted to be forced into the splined ends 35 of the return pipes. The scoop 22 may be held, during such assembly, by a magnetized tool, or a small boss (not shown) may be provided on the outer end of the scoop, by which it may be grasped.

Any suitable sort of liquid coolant, of course, may be utilized in the present construction. However, fuel utilized for producing the gas for driving the turbine may be used, if desired. By utilizing such fuel, the necessity of providing a supply of an additional liquid for operation of the turbine is avoided. Furthermore, the fuel may have a further advantage in that it will provide a ready means for closing any slight leakage between the base portions 17 of the blades and the rim 14 of the wheel. Thus, utilizing fuel as the coolant, carbonization of the fuel at the points of leakage would result from the presence of heat, pressure and lack of oxygen which are the prime conditions necessary for destructive distillation. The fuel utilized in gas turbines of the type herein contemplated is usually in the nature of kerosene and should readily carbonize under the conditions present to completely prevent any leakage. If it were desired to utilize some other liquid as a coolant or to seal any leakage before operating the turbine, a sealing film could be created in the peripheral portion of the cavity 13 by galvanizing, metalizing or enameling, introducing the material for such film in the form of a liquid or powder spray through the coolant inlet tubes. Some form of ceramic material might also be utilized.

In Fig. 7 I have shown a modified form of construction to facilitate assembly of the coolant supply means within the wheel. To this end, I make the wheel of a two-part construction comprising a pair of dished members 40 and 41, preferably shaped in substantially the same manner as the side wall portions 11 and 12 in the previously described construction. By such construction, the two dished members may be made as forgings rather than castings, if desired. The dished members or side walls 40 and 41 are provided with rim portions 42 adapted to be held in abutment with each other and preferably formed on their abutting faces in such a manner that a tight fit therebetween will be effected. In the present instance, I have shown the abutting faces as provided with coacting V-shaped grooves 43. With a construction of this character, the hub 23, together with the supply and return pipes, may be completely assembled and inserted in proper relation to the side wall 40. The side wall 41 is then placed in assembled relation with the side wall 40 and the two may be held together by means which may include or comprise peening over the outer ends of the base portions of the blades, as indicated at 44, which serves also to secure the blades in position. With this construction, the difficulty of inserting the supply and return pipes through the blade slots is eliminated.

With either of the foregoing constructions, a highly effective cooling action may be obtained. Thus, with the coolant supply held stationary, the liquid coolant is forced under pressure from the ends of the supply pipes and immediately is picked up and tends to rotate with the wheel. The high speed of the wheel produces a strong centrifugal force on the fluid and, although the fluid will not rotate at the speed of the wheel, it will be caused to move to the peripheral portion of the cavity 13 under a high centrifugal force.

and produce a scrubbing action, resulting in a rapid transfer of heat from the peripheral portion of the wheel, as well as from the base portions of the blades, to the liquid. The heated liquid, by virtue of its lesser density than the cooler liquid, will tend to be forced toward the inner portion of the rotating stream and will be picked up by the scoops 22 to be withdrawn from the wheel. The turbulence within the rotating stream created by the scoops 22 also tends to cause additional transfer of heat from the wheel to the liquid.

By cooling the wheel in this manner, heat is removed from that portion of the wheel subjected to the highest temperatures and consequently material less resistant to heat may be employed than would be the case where no cooling were effected. By the reduction of temperature in the periphery of the body portion of the wheel, such body portion may be made of somewhat lighter construction, which in turn reduces the centrifugal forces involved and the consequent stresses on the material of the body portion. In addition to cooling the periphery of the body portion, the construction herein shown also provides for the cooling of the base portions of the blades and thus is of benefit in that respect since such base portions are subjected to material stresses during operation. The present construction thus provides for cooling of all portions of the assembled wheel, which are subjected to high temperatures and relatively high centrifugal stresses.

I claim:

35. 1. A turbine wheel construction for a gas turbine, comprising a hollow rotatable body having a central opening at one face, the other face being closed, blades mounted on the periphery of said body, and means for circulating liquid 40 coolant within said body comprising a stationary hub centrally mounted within said body and having independent supply and return passages therein, a plurality of radially extending supply and return pipes carried by said hub and connected to said passages, said return passages having scoop means supported at their outer ends, and means extending through said central opening for supplying coolant to said supply passages and for withdrawing coolant from said return 50 passages.

2. A turbine wheel construction for a gas turbine, comprising a hollow rotatable body having a central opening at one face, the other face being closed, blades mounted on the periphery of said body, and means for circulating coolant within said body comprising a stationary hub centrally mounted within said body and having a plurality of concentrically positioned axially extending passages and a central bore connected to a plurality of radially extending passages, a plurality of radially extending supply pipes carried by said hub and connected to said axially extending passages, a plurality of radially extending return pipes carried by said hub and connected to said radially extending passages, and means for supplying coolant to and for withdrawing coolant from said passages comprising a pair of concentric pipes secured to said hub and extending through said central opening of the body, the 60 interior of the inner pipe communicating with said central bore and the annular space between said pair of pipes communicating with said axially extending passages.

3. A turbine wheel construction for a gas turbine, comprising a hollow rotatable body having

a central opening at one face and a centrally positioned boss extending inwardly from the other face, blades mounted on the periphery of said body, and means for circulating coolant within said body comprising a hub mounted 5 within said body on said boss and provided with supply and return passages, a plurality of supply and return pipes carried by said hub and connected to said passages, and means extending through said central opening and connected to 10 said passages for supplying coolant thereto and withdrawing coolant therefrom.
